United States Patent Office.

THOMAS P. WARREN, OF NORFOLK, VIRGINIA, ASSIGNOR TO WARREN
AND WOODHOUSE, OF THE SAME PLACE.

Letters Patent No. 65,847, dated June 18, 1867.

COMBINED COTTON-PLough AND SCRAPER.

The Schedule referred to in these Letters Patent and making part of the same.

TO ALL WHOM IT MAY CONCERN:

Be it known that I, T. P. WARREN, of the city and county of Norfolk, and State of Virginia, have invented a new and useful Combined Cotton-Plough, Iron Turner Plough and Scraper; and I do hereby declare the following to be a full, clear, and exact description of the same, reference being had to the accompanying drawings, forming part of this specification, and in which—

Figure 1 represents a perspective view of my invention, the dinters *d d'* being in position, and the mould-board *F* being removed in order to show the construction of the standard *B*.

Figure 2 shows a bottom view of the "land-side" and standard attached, other parts being removed.

Figure 3 shows the scraper-board,

Figure 4 the reversible board, and

Figure 5, the attachment for fastening the point and mould-board.

Figure 6 is the scraper-guide.

Similar letters of reference indicate corresponding parts in the several figures.

The object of my invention is the construction of an instrument which, with slight and easily made changes, hereafter explained, can be used as a cotton-plough, an iron turner plough, or a scraper, at the pleasure of the operator.

A is the "land-side" or dirt-beam of the instrument, having a projection, *a*, at its posterior end, for the purpose of attaching the handle by which to guide the plough, and being firmly attached to the upright standard *B* at its anterior end. At *d d'* are shown the dinters, which are fixed to the land-side by screw-bolts, or their equivalent, and may be removed when necessary. *C* is an attachment which is fastened to the standard *B* by screws or bolts passing through its flange, *c*, and serves as a support to the mould-point and mould-board. Its shape is shown in fig. 2. The standard *B* has an arm, *z*, at its upper extremity, by which it may be fastened to the draw-beam of the plough, and it has a wide flange, *x*, at the bottom to hold the mould-board and scraper-boards. *D* is the mould-point of the plough, attached to the standard *B* by bolts or screws *e e*. *F* is the mould-board, attached to the standard *B* in the same manner. *G* is the scraper-board, having holes, *g g*, by means of which it may be attached to the standard *B*. *H* is a reversible scraper-board, attachable to the standard *B* in the same manner by bolts through the holes *h h*. *C C* are slots in the standard *B*, through which pass the bolts that hold the scraper when they are used, or the supporting attachment *C* when the instrument is used as a plough. *K* (fig. 6) is the scraper-guide attached, when the instrument is used as a scraper, to the land-side by means of the arm *k*, one end of which is screwed to the land-side at the point *d* where the rear dinter is attached when it is used, and the other end of which passes through the hole *l* in the guide. The holes *m m m* in the opposite end of the guide are for the purpose of attaching the guide by a bolt and nut to the projection *a*, and of regulating the depth to which the guide will sink in the ground. When thus attached the guide is a blade extending below the bottom of the land-side and parallel to it, so as to cut vertically into the ground beneath the instrument, and thus prevent the scraper from sliding or yielding laterally, which a scraper is always inclined to do. An instrument thus constructed is ready for use as a corn or cotton-plough when the scrapers are detached, and the remaining parts adjusted as shown in fig. 1, the mould-board of course being in its place. By removing the mould-board *F* and the dinters *d d'*, and attaching the reversible scraper-board *H*, the instrument becomes an iron turner plough. By removing the reversible board *H*, the supporting attachment *C*, the dinters *d* and *d'*, and the point *D*, and attaching the scraper-board *G* to the standard *B*, the instrument may be used as a scraper. When the scraper-board is attached, the brace *n* should be fixed, one end to the land-side at *d* and the other, the bent end, to the scraper-board at *c*, by means of a bolt and nut, in order to steady the scraper-board. The scraper-guide is now attached, as before described. When the guide is not used, the bolt by which its rear end is attached to the projection *a* may be withdrawn and the guide reversed, so as to rest on the land-side and be entirely out of the way. This guide may be used with the iron turner plough, if necessary. It is never necessary to use it with the other plough, the dinters acting to all intents and purposes as guides. One set of bolts and screws answers for all the different modifications of my instrument.

Having thus described my invention, what I claim as new, and desire to secure by Letters Patent, is—
1. The standard B, having the broad flange α , the slots b b , and the arm γ , substantially as and for the purpose described.

2. The combination of the standard B and the flanged supporting attachment C, substantially as and for the purpose specified.

3. The scraper-guide K, attachable to the land-side in the manner and for the purpose above shown.
To the above specification of my invention I have signed my hand this first day of May, 1867.
